DUPLICATING APPARATUS

Alfred Marchev, La Grange, Ill., and Verlin M. Leach, Rushville, Ind., assignors to Ditto, Incorporated, Chicago, Ill., a corporation of West Virginia

Application May 8, 1937, Serial No. 141,386

12 Claims. (Cl. 271—61)

The present invention relates to duplicating apparatus, and more particularly to trays for positioning copy sheets to be fed to a duplicating machine.

The apparatus is shown as applied to a duplicating machine of the hectograph type. However, it is not limited thereto and may be used in connection with any tray for guiding and positioning sheets for a duplicating machine.

One form of the invention is embodied in a device of the character described, which comprises a copy sheet tray adapted to be mounted on a duplicating machine in such relation to the duplicating apparatus that the sheets positioned on the tray are fed to the duplicator after being positioned by the tray. The tray contains oppositely disposed guides which may be adjusted for different widths of sheets. In addition, the tray has mounted thereon a plurality of guides which are normally depressed below the surface of the tray when not used. The depressed guides are individually operable by pressing a button or lever to lift the selected guide above the surface of the tray.

The present invention is particularly adaptable to those duplicating operations in which the copy sheets may be in narrow strips of different widths which require their positioning at different points crosswise of the platen. One purpose of the invention is to provide a tray of the character described with a novel guide structure by which the operator can quickly select the necessary guides to properly position a copy sheet of narrow width with respect to the matter to be duplicated.

Other features and advantages of the invention will appear more readily from the following description, reference being had to the accompanying drawings, wherein a preferred form of the invention is shown.

In the drawings, Fig. 1 is a view in side elevation of a portion of a duplicating machine of the hectograph type, showing the present invention applied thereto;

Fig. 2 is a front view of the paper tray, taken substantially on the line 2—2 of Fig. 1;

Fig. 3 is a sectional view on the line 3—3 of Fig. 2;

Fig. 4 is a sectional view like Fig. 3, but showing a changed position of the parts;

Fig. 5 is a sectional view on the line 5—5 of Fig. 2, certain parts being left out for the sake of clearness;

Fig. 6 is a fragmentary sectional view, taken on the line 6—6 of Fig. 3;

Fig. 7 is a front view similar to Fig. 2, but with

a portion of the tray broken away and illustrating a modified form of the invention;

Fig. 8 is a sectional view on the line 8—8 of Fig. 7;

Fig. 9 is a sectional view, taken on the line 9—9 of Fig. 7;

Fig. 10 is a sectional view, taken on the line 10—10 of Fig. 7; and

Fig. 11 is a fragmentary sectional view, taken on the line 11—11 of Fig. 8, with the parts in a changed position from that shown in Fig. 10.

Referring now to Fig. 1, the present invention is shown as applied to a duplicating machine of the hectograph type, having a platen 10, on which a duplicating band 11 is stretched. The duplicating machine has a margin bar 12 which receives the sheets through a trough 13 from a tray 14. A platen roller 15 is adapted to press the sheets into contact with the surface of the duplicating band 11. A stack of sheets may be mounted upon a platform 16 in front of the trough 13, and, in feeding the sheets, they are positioned by the tray 14 so as to be properly aligned with the duplicating surface of the band 11. The tray 14 is fixed to the duplicating machine by a pair of brackets 17 and 18, which are secured by bolts to downturned flanges 19 and 20 at the opposite ends of the tray 14. The brackets 17 and 18 are pivoted by a pair of pins 21 and 22 to side frames 23 and 24 of the duplicating machine. The tray can thus be turned about the pivots 21 and 22 from the position shown in Fig. 1, to a position in which it overlies the platform 16. A rubber cushion member 25 is secured on the bracket 17 by a stud 26 and rests upon the side frame 23 when the tray is in the position shown in Fig. 1. A similar cushion member 27 is secured to the bracket 18 by a stud 28 and is adapted to rest upon the side frame 24.

The tray 14 has a flange 29 at its lower edge, and a flange 30 at its upper edge. The side flanges 19 and 20 of the tray 14 are connected by a tie rod 31, which is secured to the side flanges by screws 32 and 33. The tie rod 31 is utilized as a guide for a pair of sheet guiding members 34 and 35. The member 34 comprises a top plate 36 extending all the way across the tray 14 and having an upturned flange 37 along one edge thereof. On the under side of the plate 36, there are provided two felt cushions 38 and 39, one near the upper edge of the tray 14, and the other near the lower edge of the tray. The plate 36 at its upper end has a flange 40 turned down parallel to the flange 30 of the tray 14. The flange 40 is connected by a screw 41, having a knurled head 55

42, to an upturned end portion 43 of a guide bar 44. The bar 44 has upturned ears 45 and 46 which are slidably mounted on the tie rod 31. By sliding the ears 45 and 46 along the tie rod, a lateral adjustment of the plate 36 and its guiding flange 37 may be accomplished. In order to hold the plate 36 in adjusted position, the flange 40, and the end portion 43 of the member 44, are bent so as to be directed at a slight angle 10 to each other, and the screw 41 is threaded into the end portion 43, so that the tightening of the screw 41 will tend to draw the flange 40 into parallelism with the end portion 43, and this in turn tends to press the plate 36 tightly against the tray 14.

In some cases where the sheets being fed are long, it is desirable to have an upward extension above the tray 14 to support the sheets. The plate 36 is provided with a bar 47, which is secured by a pin 48 to the plate 36 near the upper edge thereof. The pin 48 extends through the plate 36, and a spring 49 is mounted under compression on the pin 48. A washer 50 presses the spring upwardly against the under side of the plate 36, and a pin 51 holds the washer 50 in place. When the operator is using long sheets, he merely turns the bar 47 about the pin 48 until it projects above the tray 14.

The member 35 is constructed in detail exactly like the member 34, except that the member 35 has its upstanding flange 52 on the opposite side, and its bar 53 is also on the opposite side, so that the flanges of the sheet guiding members are on the outside. The members 34 and 35 are too difficult in adjustment to make them readily adaptable for positioning narrow strips, or for changing quickly from one width of sheet to another. In order to provide for quick and accurate adjustments to several different widths of sheets, the tray 14 is provided with readily retractable guides 54, which can be raised above the surface of the tray by simply pressing upon a lever 55. As shown, there are four of the guides 54, although, of course, the number may be increased or decreased within the scope of the present invention. The tray 14 is provided with four spaced slots through which the guides 54 work, and the controlling mechanism for the guides is all mounted beneath the surface of the tray 14, in order to leave it unobstructed. A pair of Z-shaped brackets 56 and 57 are secured to the lower side of the tray 14 by screw bolts 58, the heads of which are countersunk in the tray 14. The brackets 56 and 57 are connected together by a plate 59 and by three tie rods 60, 61 and 62. The levers 55, which are duplicates, are all pivotally mounted upon the tie rod 62. In addition, a release lever 63 is pivotally mounted upon the tie rod 62. The type of bearing by which the levers 55 and 63 are mounted is shown in detail in Fig. 6. Two collars 64 and 65 are keyed on the rod 62 by pins 66 and 67, respectively. The collar 64 has a reduced portion 68 on the side toward the collar 65, and the collar 65 has a similar reduced portion 69, which abuts the reduced portion 68. The levers 55 and 63 are pivotally mounted upon the reduced portions 68 and 69 of the collars. The levers 55 and the lever 63 are connected to the tie rod 61 by individual springs 70, which tend to turn the levers in a counterclockwise direction about the tie rod 62.

The tie rod 60 is adapted to engage a depending portion 71 on each of the guides 54, and limit the counterclockwise movement of the levers to a position where the top surfaces of the guides 54

are in the slots in the tray 14, but just below the top surface of the tray. Each guide 54 has a tongue 72 punched out of the side thereof, which tongue is adapted to engage the under surface of the tray 14 and limit the upward movement of 5 the guide 54. The lever 63 has an extension 73, which is similar in shape to the depending portion 71, and which is adapted to engage the tie rod 60 to limit the counterclockwise movement of the lever 63. The depending portions 71 of the guides 54 are provided with notches 74 at their free ends and, in addition, they have camming surfaces at 75. The notches 74 and the camming surfaces 75 cooperate with a latch bar 76 that is pivoted in the brackets 56 and 57 to 15 latch the guides 54 in raised position when they are lifted by pressure on the levers 55. The latch bar 76 is connected by a spring 77, under tension, to the tie rod 61. The extension 73 of the lever 63 has a camming surface 78, which is 20 adapted to engage the latch bar 76, but it has no notch corresponding to the notch 74.

In operating, if it is desired to elevate any one of the guides 54, the corresponding lever 55 is pushed down by pressing upon one of the knobs 25 79 provided on the levers 55. The pushing down of the lever 55 lifts the corresponding guide 54 until the tongue 72 strikes the lower surface of the tray 14. When the guide is raised into this upper position, the latch bar 76 is drawn by the 30 spring 77 into the notch 74 so as to latch the guide 54 in raised position. When the operator wishes to change the guide to elevate another one of the guides 54, he merely presses the corresponding knob. When the new guide is rising, 35 its camming surface 78 forces the latch bar 76 out of the notch 74 of the guide which is in raised position, and thus permits that guide to return to retracted position, which it will do because of the tension exerted by the spring 77. The latch 40 bar 76 will then lock the new guide in raised position by swinging into the notch 74 thereof. When it is desired to have two of the guides in use at once, as, for example, in the feeding of a very narrow strip between two of the guides, the operator depresses both levers at once. When it is desired to bring all of the guides into retracted position, the operator merely depresses the release lever 63, and the camming surface 78 of its extension 73 will force the latch bar 76 out of the 50 notches 74 of all raised guides, and allow them to return to retracted position.

In Figs. 7 to 11 inclusive, a modified form of the invention is shown, in which the individual guides may be raised individually, without releasing the 55 guides that are already in elevated position. In this form of the invention, the guides 54, their levers 55, and the associated operating mechanism, including the release lever 63, remain substantially the same as in the form of the invention shown in Figs. 1 to 6. In the modified form of the invention, a rock shaft 80 is pivotally mounted in the brackets 56 and 57. Alongside of each of the depending portions 71 of the guides 54, the rock shaft 80 has a pin 81. The pins 65 mount latch bars 82, which are bent around the shaft 80, and provided with elongated slots 83 and 84, which permit of a limited rocking movement of the latch bars 82 upon the shaft 80. The depending portions 71 of the guides 54 are provided with tongues 85, which are turned at right angles to the guides 54 into the paths of the latch members 82. On each latch member 82, a shoulder is provided at 86, which is adapted to engage under the tongue 85, so as to provide an addi- 75

tional latch to hold the guide 54 in raised position. The shoulder 86 is formed by the upper end of the latch member 82. A plate 87 is secured on the latch member 82 and projects above the shoulder 86, so as to form a stop which limits the clockwise movement of the latch member 82 when it is holding the guide 54 in raised position. Springs 88 connect each of the latch members 82 to the tie rod 61.

10 The release lever 63 has no connection with the rock shaft 80, but an auxiliary release lever 89 is pivoted on the tie rod 62 and has an extension 90 which is adapted to engage a release arm 91 that is keyed to the shaft 80. The release arm 91 has no play upon the shaft 80, but moves directly with it. Now, when it is desired to lift any one of the guides 54, the operator presses down upon the corresponding lever 55, and the guide, when lifted, will be held in raised position by the latch bar 76 engaging in the notch 74. In addition, the individual latch member 82, associated with the depending portion 71 of the raised guide, will engage the corresponding tongue 85. Then, if the operator desires later to lift a second guide, to 25 cooperate with the first guide raised, he merely depresses the lever for the guide he desires to lift, and it in turn will be latched in raised position by the bar 76 and the individual latch bar 82 associated with it. The bar 76 will, of course, release the first raised lever. However, the individual latch bar 82 will hold the first raised lever in raised position. The tongue 85, upon the guide being raised, will rock its corresponding latch lever 82 in a counterclockwise direction, but 30 not to a sufficient degree to cause the shaft 80 to rock the lever 82, holding the raised guide, sufficiently to release it. When it is desired to release the raised guides, then both the release lever 63, and the auxiliary release lever 89, are depressed. 35 This releases the latch bar 76 from holding position and turns all of the individual latch levers 82 far enough in a counterclockwise direction to release them from the corresponding tongues 85.

While certain embodiments of the invention have been shown and described, it is to be understood that it is capable of many modifications. Changes, therefore, in the construction and arrangement may be made without departing from the spirit and scope of the invention, as disclosed 45 in the appended claims, in which it is our intention to claim all novelty inherent in the invention as broadly as possible in view of the prior art.

Having thus described the invention, what we claim as new and desire to secure by Letters Patent is:

1. In a duplicating machine, a sheet positioning tray, a sheet guide on said tray, said guide being movable from a functionally inoperative position below the sheet receiving surface of said tray to a functionally operative position where it projects above said surface.
2. In a duplicating machine, a sheet positioning tray, a sheet guide on said tray, said guide being movable from a functionally inoperative position below the sheet receiving surface of said tray to a functionally operative position where it projects above said surface, said tray having a slot therein and said guide being positioned in said slot.
3. In a duplicating machine, a sheet positioning tray, a sheet guide on said tray, said guide being movable from a functionally inoperative position below the sheet receiving surface of said tray to a functionally operative position where it projects above said surface, a lever for lifting said guide,

and latch means holding the lifted guide in raised position.

4. In a duplicating machine, a sheet positioning tray, a sheet guide on said tray, said guide being movable from a functionally inoperative position below the sheet receiving surface of said tray to a functionally operative position where it projects above said surface, said tray having a slot therein and said guide being positioned in said slot, and latch means for holding the guide 10 raised above the tray surface.

5. In a duplicating machine, a sheet positioning tray, a sheet guide on said tray, said guide being movable from a functionally inoperative position below the sheet receiving surface of said tray to 15 a functionally operative position where it projects above said surface, and latch means for holding the guide raised above the tray surface.

6. In a duplicating machine, a sheet positioning tray, a sheet guide on said tray, said guide being 20 movable from a functionally inoperative position below the sheet receiving surface of said tray to a functionally operative position where it projects above said surface, latch means for holding the guide raised above the tray surface, and a manually operable trip lever for releasing the latch means.

7. In a duplicating machine, a sheet positioning tray, said tray having a plurality of spaced sheet guides thereon, said guides being movable 30 through the tray between a functionally inoperative position below the sheet receiving surface of said tray and a functionally operative position where they project above said surface.

8. In a duplicating machine, a sheet positioning 35 tray, said tray having a plurality of spaced sheet guides thereon, said guides being movable through the tray between a functionally inoperative position below the sheet receiving surface of said tray and a functionally operative position where they 40 project above said surface, and manually operable levers for lifting said guides to functionally operative position.

9. In a duplicating machine, a sheet positioning tray, said tray having a plurality of spaced sheet 45 guides thereon, said guides being movable through the tray between a functionally inoperative position below the sheet receiving surface of said tray and a functionally operative position where they project above said surface, manually operable 50 levers for lifting said guides to a functionally operative position, and latch means for holding the lifted guides in place.

10. In a duplicating machine, a sheet positioning tray, said tray having a plurality of spaced sheet 55 guides thereon, said guides being movable through the tray between a functionally inoperative position below the sheet receiving surface of said tray and a functionally operative position where they project above said surface, manually operable 60 levers for lifting said guides to a functionally operative position, and latch means for holding the lifted guides in place, said latch means comprising a latch bar and a trip lever for releasing said latch bar.

11. In a duplicating machine, a sheet positioning tray, said tray having a plurality of spaced sheet guides thereon, said guides being movable through the tray between a functionally inoperative position below the sheet receiving surface of 70 said tray and a functionally operative position where they project above said surface, manually operable levers for lifting said guides to functionally operative position, individual latch means for holding said guides in functionally operative 75

position, and release means for said individual latch means.

12. In a duplicating machine, a sheet positioning tray, said tray having a plurality of spaced sheet guides thereon, said guides being movable through the tray between a functionally inoperative position below the sheet receiving surface of said tray and a functionally operative position where they project above said surface, manually

operable levers for lifting said guides to functionally operative position, a latch bar for latching the guides in raised position when lifted, individual latch members for latching the guides in raised position, a trip lever for said latch bar, and release means for said latch members. 5
